1**2,751,141****MULTIPLY PAPER SACKS**

William Vincent Owens, Northfleet, England, assignor to
Paper Sacks Limited, Bristol, England

Application July 7, 1952, Serial No. 297,491

Claims priority, application Great Britain July 12, 1951

3 Claims. (Cl. 229—55)

This invention relates to multiply paper sacks of the kind in which longitudinal slits are formed which extend inwardly from the ends of the sack such that on closing the ends of the sack the end triangular formations terminate in an inward portion having parallel edges extending transversely across the sack while the side folding formations have parallel edges extending longitudinally of the sack. When the various plies of the sack are assembled these slits are coincident and it has been found there is a danger of the plies tearing at this point, and there is also a risk of seepage of the contents of the sack.

It is an object of the invention to provide an improved construction of sack of the kind described whereby the above disadvantages are eliminated.

The invention consists in a multiply paper block bottom bag wherein the bag tube plies are transversely perforated at bag length and are longitudinally slit to provide corner forming parts such that when the plies are assembled the slits are transversely staggered to provide said corner forming parts of increasing width from the outer to the inner ply, the length of such parts being equal in all plies.

According to the invention in a multiply paper sack of the kind described the slitting of the various plies is located at different distances from the longitudinal axes of the webs whereby when the webs are assembled the slits are relatively staggered and corner forming parts of varying width are formed which provide exposed portions of each ply for adhesive sealing.

The relative lateral displacement of the slits may vary as desired.

The invention may be applied to a multiply sack having staggered end margins and in such the relative displacement of the slits will provide a sealing area of each ply at the ends of the side closing flap.

In the accompanying drawings,

Figure 1 illustrates a layout of one end of the ply sheets of a bag constructed according to the invention;

Figure 2 illustrates the plies of Figure 1 separated from one another;

Figures 3, 4 and 5 illustrate the steps in folding an end closure.

In carrying the invention into effect according to one convenient mode by way of example, as applied to the manufacture of a 3-ply sack, a series of webs 1, 2, 3, are fed from supply reels to an assembly position to provide a composite web. Each web is transversely perforated for sack length. Thus, at the corresponding ends of a set of bag lengths, the intermediate ply 2 will be perforated on a rectilinear line 2a, while the inner ply 1 and the outer ply 3 will have shouldered and notched perforations 1a and 3a respectively. Each ply is longitudinally slit on both sides of the perforation to form the parallel edges of the folding in end triangular formation. The slitting of the outer ply 3 is shown at 21; that of the intermediate ply 2 is shown at 23 while that of the inner ply 1 is shown at 24. This slitting is effected equidistantly from the edge folding lines 22 of the sack length. It will be

2

noted that the slits are shown open for clarity and that there is no removal of material. The position of the slits 21, 23, 24 in the various webs 3, 2, 1 is appropriately displaced transversely so that the distance between such parallel edges of the triangular folds on the plies will increase from the outermost ply to the innermost ply, as seen in Figure 3. In other words when the corner formation of the sack length 28 is folded the intermediate ply 2 and inner ply 1 will have exposed areas 29, 30 at such parallel edges. Correspondingly there will be exposed areas 33 at the ends of the outer ply on the side flap 31 and exposed areas 34, 35 on the outer and intermediate plies 3 and 2 at the ends of the side flap 32.

The disposition and shape of the perforations 1a, 2a, 3a is such that when the webs 1, 2 and 3 are assembled and the sack length severed by tension thereon the end margins on the sack length will be staggered as indicated in Figure 1 and the transverse edges of the portions 25, 26, 27 will coincide.

The relative disposition of the longitudinal slits 21, 23, 24 in the webs may vary with corresponding marginal exposure of the plies when folding to form the bottom closure.

The longitudinal extent of the longitudinal slits 21, 23, 24 is preferably such that when the end is folded the inner ends of the slits coincide with the folded edges 28a of the end triangular formation 28, such edges being indicated by the lines 28b in Figure 1.

With the relative transverse disposition of the slits 21, 23, 24 the risk of tearing of the plies is eliminated with consequent avoidance or lessening of seepage.

Moreover, in the closing of the end of the sack additional surface area of the various plies will be exposed and be available for adhesively securing the side folding portions to one another at their ends and also to the end fold portions.

In the first fold in forming the block bottom closure as illustrated in Figure 3 the triangular corner of formation 28 will include the transverse exposed areas 29, 30 which will be available for adhesive sealing.

In the next fold illustrated in Figure 4 the exposed areas 34, 35 of side flap 32 will be adhesively secured to the outer ply of the corner formation 28, the exposed parts 29, 30 of such flap also being adhesively secured to the same ply.

In the final fold illustrated in Figure 5 the exposed areas 29, 30 and the staggered margin areas 36, 37 and 38 will be adhesively secured to the corner formation 28 and the parts 39, 40, 41 of the folded over side flap. In this final fold the outer ply of side flap 31 will provide an integral label 42 having exposed sealing areas on all sides.

At the corner of the bag to form the valve the pasting will be such as only to avoid sealing to the corner flap, and an inwardly extending valve sleeve may be provided at such corner.

I claim:

1. A multiply paper bag having an end block bottom closure comprising a pair of side flaps of rectangular shape and a pair of end flaps of combined triangular and rectangular shape, the plies of the side flaps being stepped longitudinally of the bag so that the plies of a first one of said side flaps are progressively longer from the inner to the outer ply, while the plies of the second one of said side flaps are progressively longer from the outer to the inner ply, the lateral edges of both the side flaps being stepped to expose areas of all plies for adhesive sealing, the inner terminal edges of the plies of both of the end flaps being coincident, the lateral edges of the plies of the rectangular portions of the end flaps being stepped to expose areas of all plies for adhesive sealing, said second side flap being turned over a line transverse to said bag length and adhered to parts of said end flaps, and said first side

flap being turned over a line transverse to said bag length and having its stepped plies overlying and adhered to parts of said end flaps and the stepped plies of said second side flap.

2. A multiply paper bag in accordance with claim 1, 5 in which the plies forming said bag are slit longitudinally at respectively different distances from the longitudinal center line of the bag to provide the stepped relationship of the lateral edges of the side and end flaps.

3. A multiply paper bag in accordance with claim 2, 10 in which the bag is formed of three plies, with the outer and inner plies having portions terminating on transverse lines spaced longitudinally from the termination of the

same portions of the central ply, to provide the stepped relationship of the lengths of the plies forming said side flaps.
